CLASSIFIER FOR SOLID MATERIAL.

1,074,301.

Specification of Letters Patent. Patented Sept. 30, 1913.

Application filed June 29, 1911. Serial No. 636,038.

To all whom it may concern:

Be it known that I, RENÉ EMILE TROTTIER, citizen of the Republic of France, and resident of 84 Rue de la République, 5 Puteaux, Seine, in the said Republic, engineer, have invented a new and useful Classifier for Solid Material, of which the following is a specification.

This invention relates to a classifying apparatus designed for the mechanical separation of solid bodies, particularly ores, according to their specific gravity while classifying them by volume in each order of their specific gravity, the apparatus being 10 also constructed to classify by subsidence the fine particles which have escaped classification by specific gravity.

The apparatus is based essentially upon the combined use of three simultaneous actions on the materials to be classified, that is to say the resistance of the medium, the difference in the action of momentum and the resistances due to inertia and friction. The resistance of the medium, in this case 20 the liquid in which the classification is effected, allows when the materials are free in the medium a classification of them in the vertical direction according to the order of their specific gravities, the heaviest being collected at the lowest part. The difference in the action of momentum on the materials during their movement in the classifying medium produces a classification also according to the specific gravity 25 but in the horizontal direction. The effect of these two actions is further increased by the resistances due to the inertia of the materials and to their friction on the parts which carry them (liquid medium and mechanical devices), in such a manner that the resultant of this triple action gives rise 30 to a lateral travel in opposite directions of two materials of different specific gravities, that is to say if the classification is effected 35 on a table of suitable inclination, the particles of the heavier material may be caused to advance and those of the lighter material to recede.

A practical embodiment of the invention 40 is represented in the accompanying drawings, in which,

Figure 1 represents diagrammatically the principle of the invention; Fig. 2 represents a longitudinal vertical section through the 45 apparatus, and Fig. 3 represents a top plan view thereof.

The apparatus consists essentially of a sieve 1 which is extended by a table 2 and together with this table is fixed to a frame 3, suspended by two connecting rods 4 and 5 within a vat 6 containing water. The sieve 1 and the table 2 form with the horizontal, angles suitable to the nature of the particles under treatment. By means of the connecting rod 7 an obliquely acting 50 force is applied so as to give to the system 1, 2, 3 a suitable oscillating movement.

The connecting rod 7 forms an angle α with the horizontal, generally different from 90° , and the connecting rods 4 and 5 form 55 the angles β and γ respectively with the horizontal. If by means of the connecting rod 7, the sieve be oscillated, the materials charged on to the latter for the purpose of classification will travel on the sieve more 60 or less rapidly and in the desired direction under the effect of the combined triple action defined above, which action may be accelerated or retarded according to the respective values of angles α , β and γ . If one 65 considers a particle 8 carried by the sieve, this particle will be raised slowly by the sieve during its upward movement until the particle has the position 9; at this point it is left, because the sieve descends suddenly 70 from beneath it, so that it falls back on to the sieve between the points 8 and 10 when the sieve has arrived at its original position, the distance of this point from the original 75 point 8 being a function of the specific gravity of the particle. Assuming that there are two particles of different specific gravities and that the angles α , β and γ have a suitable 80 value and that the movement has a certain amplitude, the two particles, instead of advancing simultaneously, fall on the sieve at different points, the lighter being below the point 8 and the heavier above this point. It follows that the lighter particles recede 85 while the heavier particles advance on the sieve. This displacement of the particles, owing to the movement of the sieve, is also favored by the current developed in the liquid by this movement, which current acting 90 with a suitable force and in appropriate directions accentuates the separation of the particles by circulating across them when they are already more or less lifted according 95 to the order of classification.

The ore to be classified being composed, for example, of three minerals 11, 12, and 13, of different specific gravities, these min- 100 105 110

erals will be separated on the sieve 1 in three superposed layers following each other, as is indicated in Fig. 1, since, as has been explained, the heavy particles of the layer on 5 the sieve advance and the light particles recede. It follows that by limiting the intermediate layers, in this case layer 12, by a transverse discharge there will be obtained on the surface of the sieve, a clean separation 10 of the zones of the different layers. By suitably adjusting this discharge the several layers will have a sufficient thickness to insure that each layer of a given specific gravity, acting like an imperfect liquid, will form 15 a bed practically impenetrable to particles of lower specific gravity, in such a manner that each section of the sieve will only allow to pass materials strictly of the same specific gravity, which can therefore be collected separately. Moreover, in each layer of the same specific gravity of the bed the materials will be classified successively according to their volume by spreading themselves out on the sifting surface, the volume diminishing from 20 the front to the rear in such a manner that by suitably selecting the mesh of the sieve and the transverse discharge for each of the zones, it is possible to collect separately materials of the same specific gravity but of 25 different volume. Finally, the fine materials which, in consequence of their fineness and of the necessary movement of the classifying medium, have been able to escape the classification by specific gravity and by volume, may by a suitable modification of the 30 characteristics of the current be classified by subsidence in the same medium by introducing after the sieve boxes in which the fine materials are successively deposited.

40 In the arrangement shown the vat 6 is of rectangular form and has at its lower part a number of compartments shaped like hoppers, in this case seven compartments 14, 15, 16, 17, 18, 19 and 20. Above the compartments 17, 18 and 19 is suspended the frame 3 provided with the oscillating sifting surface. This surface is composed of a number of like parts equal to the number of materials to be separated and each consisting of 45 a sieve 1, inclined from the front end to the rear end, and a table 2 being an extension of the sieve and inclined in the opposite direction. These sieves and their tables are each inclined to the horizontal to a degree related 50 to the nature of the material under treatment; this angle of inclination may be in consequence different from one sifting surface to another as shown for instance in Fig. 2.

55 The frame 3 is supported by two pairs of connecting rods, of which the rear pair 4, pivoted at 21 to the wall of the vat, are of constant length, while the front pair 5, connected with the upper and lower spindles 6, are of adjustable length so that their

inclination may be varied. For this purpose the connecting rods 5 terminate at their upper parts in racks 22 engaged by pinions 23 carried by the upper spindle 24. The lower spindle 25 against which the connecting rods 5 are applied by hooks carries pinions 26 in gear with racks 27 fixed on the upper edges of the sides of the frame 3. It will be understood that the angle γ which the connecting rods 5 make with the horizontal can be varied by turning pinions 23 and 26, and by fixing or not the spindles of these pinions. This mode of adjusting and pivoting the connecting rods 5 thus insures always the desired compensation according to the amplitude of the oscillation and the value of the angle α of the connecting rod 7 which transmits the motion. This latter rod, which is made in two parts connected by a nut 28 so as to be adjustable in length, is pivoted at 29 to a lever 30 itself pivoted to the vat; the pivot 29 may be shifted on the lever so as to vary the angle α . The adjustment of the length of the connecting rod 7 by operation of the nut 28 serves to 35 vary the angle β of the connecting rods 4. Thus means are provided for varying suitably the three angles in question so as to adjust the apparatus for the conditions of classification.

45 On the driving shaft 31 which is driven through a pulley 32 is keyed a cam 33 for lifting the lever 30. The descending movement of this lever is stopped by a cross bar 34 which may be placed at any desired 50 point on the upper edges of the vat so as to allow the desired amplitude of the movement agreeable to the position given to the pivot 29 of the connecting rod 7 on the lever 30. This arrangement produces a 55 slow rising movement of the sieve and a rapid descent thereof. The sudden arrest of the descending movement by the bar 34 also has the advantage of insuring automatically the clearance of the sieve. When 60 the apparatus is in operation, the vat being suitably filled with water, the movement of the sieve and of the water which traverses it produces several beds which overlap each other on the sieve in the manner indicated 65 above with reference to Fig. 1. The rising tables 2 of each sifting surface (except the first), constitute stops which limit the end of the layers of the bed while permitting easy 70 advance of the dense particles rejected by 75 the lower bed; they thus insure that the layers will have sufficient thickness to make them impenetrable to particles of lower 80 specific gravity. But as at the base of the beds there will tend to form an accumulation 85 of particles of maximum dimensions which will be unfavorable to the impenetrability of the bed, there is arranged between the adjacent ends of the surfaces a 90 transverse opening beneath which runs a 95

gutter or other receiving device, such as 35, which discharges laterally into the hopper 18 the material which it receives, so as to leave the bed on the sieve quite homogeneous. At the rear end of the sieve is arranged an adjustable ledge 37 sliding in a groove and provided at its lower part with a flexible metallic cloth, this ledge being for the purpose of adjusting the height of the lower bed of the lightest materials (13 in the example shown in Fig. 1).

In each layer of the bed, the particles classify themselves along the sieve according to the respective volumes and for this purpose the mesh of the sifting surface may have appropriate dimensions, so that when it is desired to classify by volume it suffices to collect apart beneath the sieve the different orders of volume to be separated. In this case the lower part of the apparatus is partitioned into a suitable number of boxes.

The apparatus is fed as regularly as possible above the sieve at 36 (Fig. 1) toward the upper point of which the lightest materials to be classified (the gangue in the case of minerals) advances.

The movement of the frame gives rise to a continuous circulation of water around the sieve in the direction of the arrows 38. Movable baffles 39 situated along the lines of separation of the hoppers serve, as may be desired, to direct the current of water against the lower face of the sieve, so as to lift the material above this latter, while entraining the fine material remaining in suspension after having passed through the sieve. The several tables 2 of the sifting surface serve moreover to maintain and to direct the current of water, thus increasing its action on the materials which descend the slope of the sieve. There may also be added at other points of the frame beneath the sifting surface, tables such as 40, if it be desired for example to prevent a material from re-mounting the slope.

The fine material traversing the sifting surface and too light to descend directly into the hoppers 18 and 19 is entrained by the current of water and carried to the right hand end of the apparatus above the hoppers 14, 15, 16 and 17 where it is deposited. There is thus a successive classification of the light materials by subsidence in the hoppers. To aid this classification, water may be fed to the vat through vertical pipes 41, extending nearly to the bottom of the hoppers in which these materials are classified; the arrangement being similar to that of the well known apparatus called "spitz-kasten." There is obtained in this manner a complete apparatus which classifies by subsidence materials which have escaped the main classification by specific gravity. Above the last hopper 14 there may be arranged a deflecting plate 42 for aiding the

reversal of the current of water so as to cause it to flow back above the sifting surface. An overflow 43 carries off the excess of water.

The removal of the materials collected in the several hoppers may be effected through cocks or valves 44 arranged at the base of each and controlled either by hand or automatically. It is advantageous to use for this purpose an automatic discharging apparatus of the kind shown at the base of the extreme left hand hopper 20. This device consists of a receiver 45 connected with the outlet of the hopper by a flexible connection 46, the lower end of this receiver is closed by a valve 47 carried by a lever 48 pivoted to the receiver and connected with a connecting rod 49 itself pivoted to the wall of the hopper; a spring 50 tends to keep the valve 47 closed and to bring the receiver into the normal inclined position. When the receiver 45 is full its weight destroys the equilibrium and it assumes a lower position overcoming the force of the spring 50. In consequence of the movement of the connecting rod 49 and of the lever 48 around their pivots, the valve 47 is opened and the material is suddenly ejected from the receiver; the receiver being thus unloaded is raised under action of spring 50 and the valve 47 closes so that the filling of the receiver begins again, thus the discharge is automatic and intermittent and a minimum quantity of water is lost.

Having thus described my said invention and the best means I know of carrying the same into practical effect, I claim:

1. An apparatus for classifying solid materials by specific gravity and in each order of specific gravity by volume, comprising a frame, a series of inclined sifting surfaces carried by the said frame, tables extending the said surfaces and inclined in the opposite direction thereto, transverse discharge gutters, separating the sifting surfaces, a vat sub-divided at its lower part into compartments corresponding with the several sifting surfaces, water filling the said vat and means for imparting to the sifting surfaces an oscillating movement and means for communicating to the water a movement around the said surfaces.

2. An apparatus for classifying solid materials by specific gravity and in each order of specific gravity by volume, comprising a frame, inclined sifting surfaces carried by the said frame, tables of inclination opposite to that of the sifting surfaces separating these surfaces, inclined walls fixed to the frame beneath the said surfaces, a vat filled with water in which the frame is immersed, compartments formed at the lower part of the said vat and corresponding with the several sifting surfaces, movable baffles of adjustable inclination arranged at the lines

of separation of the said compartments and means for communicating to the said frame an oscillating movement and means for imparting to the water a movement around the said surfaces.

3. An apparatus for classifying solid materials by specific gravity and in each order of specific gravity by volume, comprising a frame having an oscillating movement, inclined sifting surfaces carried by the said frame, a vat filled with water in which the said frame is immersed, compartments formed at the lower part of the vat beneath the sifting surfaces, other compartments formed in front of the said surfaces, pipes adapted to admit water and opening at the bottom of the last-named compartments, inclined walls fixed to the frame, beneath the sifting surfaces, inclined movable baffles located at the points of separation of the compartments formed under the sifting surfaces, and means for imparting to the water a movement around said surfaces.

4. An apparatus for classifying solid materials by specific gravity and in each order 25 of specific gravity by volume, comprising a frame, inclined sifting surfaces carried by the said frame, tables of inclination opposite to that of the sifting surfaces separating these surfaces, inclined walls fixed to the 30 frame beneath the said surfaces, a vat filled with water in which the frame is immersed, compartments formed at the lower part of the 35 said vat and corresponding with the several sifting surfaces, means for communicating to the said frame an oscillating movement, and means for imparting to the water a movement around the said surfaces.

In testimony, that I claim the foregoing as my invention, I have signed my name in 40 presence of two witnesses, this 19th day of June 1911.

RENÉ EMILE TROTTIER.
